DRIVE FOR CONTINUOUS PROCESSING MACHINES

Hans W. Sachs, Binghamton, N. Y., and Charles C. Borck, Chicago, Ill., assignors to Remington Rand Inc., Buffalo, N. Y., a corporation of Delaware

Application April 17, 1947, Serial No. 742,058

5 Claims. (Cl. 271—2.3)

1

This invention relates to a drive mechanism for continuous film processing machines adapted for handling continuous strips of film, paper, etc.

The invention deals particularly with the type of continuous film processing machine shown in Patent No. 2,146,170 patented February 7, 1939, and improves the friction drive mechanism used in machines of the type shown in said patent.

Machines of the type shown in the aforementioned patent are subject to disadvantages that render their operation inefficient and unsatisfactory, because of excessive resistance to rotation on the part of idle spools, and resistance due to liquid drag acting on the film loops suspended over the idle spools. The liquid drag causes accumulation of slack on idle spools which the drive mechanism is unable to control because of excessive tension on film strands engaged with the driven spools. While the drive mechanism of prior art machines for each successive bank of spools is constructed to drive the spools in each successive bank slightly faster than the preceding bank for the purpose of preventing slack, and at the same time allowing slippage in the drive mechanism to prevent excessive tension on the film strip from breaking or damaging the film; it has been found that by reason of the foregoing disadvantages, the tension on the film at the driven spools slows down the film feed at the driven spools so that slack will progressively develop on the idle spools which the driven spools are unable to eliminate. As soon as sufficient slack accumulates, the film will scrape the tank walls and tangle with adjacent parts of the apparatus and become damaged.

The present invention eliminates these disadvantages and provides for substantially uniform feeding of the film with the elimination of slack in the loops on idle spools, at the same time controlling the tension on the film to prevent excessive tension. This is accomplished by providing a drive mechanism in each spool bank having friction drive means for positively driving the shaft carrying the upper set of film spools and a positive friction drive for a selected spool or spools. This drive arrangement tends to rotate all of the idle spools, where they are freely rotatable on the shaft so that they will tend to rotate at the speed of the positively driven shaft while the driven spools positively feed the film and through disengageable friction contact of a drive pulley therewith, provide for control of tension on the film and elimination of slack in cooperation with the shaft drive. The friction

2

drive for the spool shaft is preferably arranged so that tension on the film will operate the spool shaft so as to disengage the drive for the shaft independently of the disengagement of the friction drive for the spools through excessive film tension.

In the drawing:

Fig. 1 is a vertical cross-section through a processing tank showing the upper portion of a film supporting and drive mechanism in elevation.

Fig. 2 is a vertical cross-section taken on line 2—2 of Fig. 1.

Fig. 3 is a fragmentary cross-section similar to Fig. 1 showing a modified construction.

Fig. 4 is a vertical cross-section taken on line 4—4 of Fig. 3.

The processing machine to which the present invention is applied provides a support 1 which may be one of a plurality of tanks for developing, fixing and washing photo-sensitized film and other apparatus for treating the film such as drying and the like, of any suitable construction. Angle members 2 are mounted in spaced parallel relation along opposite upper side edges of support or tank 1 and provide the means for supporting the film carrying and feeding mechanism. The film supporting mechanism provides upper and lower spaced parallel shafts carrying a plurality of film spools, only the upper shaft being illustrated at 4 carrying a plurality of film spools 5. Shaft 4 is rotatably mounted at opposite ends in ball bearings or the like 6 carried by saddles 7 slidably mounted on pairs of spaced parallel rods 8, at opposite sides of the tank, as disclosed in said patent. Saddles 7 are supported on pairs of spaced parallel rods 9 extending through the lower flanges of each angle member 2 for vertical movement therein and resiliently supported by springs 10 engaged about rods 9 above angle members 2. Nuts 11 threaded on the upper ends of rods 9 engage the upper ends of springs 10 and provide means for adjustably supporting saddles 7 and opposite ends of shaft 4 in resiliently suspended relation in tank 1 from angle members 2.

The lower shaft arranged in spaced parallel relation to shaft 4 is supported by rods 8 and provided with a plurality of film spools for cooperation with spools 5 in having the film strip looped over spools 5 and the spools on the lower shaft to provide a spool bank on which film is supported in support or tank 1 for movement therethrough during processing. This construction as disclosed in the drawing and herein de-

scribed, corresponds to similar structure in the aforementioned patent.

Spools 5 are rotatably mounted on shaft 4 and retained in adjacent relation against endwise movement by collars 12. Film is fed in any suitable manner over guide spool 13 rotatably mounted on bracket 14 carried by one of the angle members 2 and provides a film entering position on a processing machine from which the film is fed to the first bank of film spools and looped over the spools 5 of the first bank on upper shaft 4 and the corresponding spools on the lower shaft in substantially the same manner as disclosed in said patent. When the film leaves this first bank of film spools 5, it is then extended to a second bank of film spools similar to this first bank where the film is looped over the respective spools on the upper and lower shafts and then successively passed to successive spool banks in a similar manner. Each of the spool banks is mounted on or suspended in supports or tanks 1, or other processing equipment, in the manner hereinabove described, and as further disclosed and described in said patent.

The present invention provides for the rotatable mounting of shafts 4 in ball or like bearings, as distinguished from the fixed mounting of the corresponding shaft in the aforementioned patent. In addition, the present invention provides a driven disc 15 rigidly secured to one end of shaft 4 in any suitable manner and having a periphery of less diameter than the periphery of film spools 5.

The film drive mechanism has a drive shaft 16 for each spool bank. One end of each drive shaft 16 is mounted in a bearing 17 on one angle member 2, as illustrated in the drawing, while the opposite end has a bearing in gear box 18 on the other angle member 2. A bevel gear 19 is mounted on the free end of shaft 16 in gear box 18 in mesh with bevel gear 20 mounted on longitudinal drive shaft 21 driven by a suitable source of motive power. This mounting of shaft 16 is similar to that shown in the aforementioned patent.

A drive pulley 22 is mounted on one end of shaft 16 adjacent one angle member 2, as shown in the drawing, and provided with a peripheral band 23 providing a friction drive surface on the periphery of the drive pulley for engagement with the periphery of driven disc 15 for positively rotating shaft 4 by means of drive pulley 22 and driven disc 15 in the rotation of shaft 16. This drive arrangement provides part of the feature of the present invention.

A drive pulley 24 has a peripheral band 25 thereon and is rigidly secured to drive shaft 16 at the end opposite drive pulley 22 adjacent the other angle member, as shown in the drawing. The periphery of band 25 provides a friction drive surface on drive pulley 24, normally adapted to frictionally engage the periphery of one or more film spools 5 at the end of the spool bank from which the film leaves the bank. The diameter of drive pulley 24 is less than the diameter of drive pulley 22 so shaft 4 is driven at a faster rate of speed than film spools 5. This provides a tendency drive for the idle film spools 5 at a rate of speed faster than that of film spools 5 driven by drive pulley 24.

It is the purpose of the present invention to control slack, distribute tension and maintain substantially uniform film feed with control of the feed to prevent excessive tension within each spool bank, as distinguished from the control of

slack and tension requiring the drive and control means in adjacent banks to cooperate as in previous types of construction. It has been found that the feed of film in a bank to avoid excessive tension and slack can best be obtained by having the drive means located where it will pull the film through the spool bank. It has been found that when the film leaves the driven spools, that it will not feed over succeeding spools in the direction of feed except to produce slack. It is, therefore, necessary that the drive means for each spool bank throughout the processing machine, provides means for pulling the film into and through the spools in the bank and it is by this feature of the present invention that control of slack and tension on the film may be obtained in each spool bank independently of adjacent spool banks. Film being processed may be successfully fed at high speed according to the present invention without developing slack or excessive tension.

In operation, the drive mechanism hereinabove described provides for the positive drive of shaft 4 carrying upper film spools 5, so that all of the idle film spools 5 will have a tendency through the friction between the bore of the spool and shaft 4 to rotate with shaft 4 at a faster rate of speed than driven spools 5 engaged with drive pulley 24. This eliminates the formation of slack on the idle spools previously occasioned by reason of the idle spools normally not rotating until caused to do so by frictional engagement of film therewith during feeding movement of the film strip through the spool bank. This normal tendency of idle spools 5 to rotate with shaft 4 at a faster rate of speed than the film feed, will tend to aid in the feed of the film to avoid slack caused by liquid drag on the film strip in the processing liquid in tanks 1.

Whenever this tendency drive of idle film spools 5 creates sufficient tension in the film strip engaged over idle spools 5, it will move the end of shaft 4 carrying driven disc 15 downwardly. Saddle 7 at one side of the tank adjacent disc 15 moves downwardly with rods 9 against the tension of springs 10. By this operation, the periphery of driven disc 15 will disengage the periphery of drive pulley 22 so that rotation of the shaft will slow down until the tension on the film engaged on the idler spools is relieved whereupon the periphery of driven disc 15 will again engage the periphery of band 23 of drive pulley 22.

This operation of shaft 4 at one end will not affect or cause driven spools 5 engaged with the periphery of band 25 of drive pulley 24 to disengage from the drive pulley, because shaft 4 moves about the point of contact between the periphery of driven spools 5 and band 25 of pulley 24 as a pivot. Whenever the tension on the film strip engaged with driven spools 5 becomes excessive, it will overcome the tension of springs 10 at the side of the machine adjacent driven spools 5 so that saddle 7 will move downwardly and the peripheries of driven spools 5 will disengage from the periphery of band 25 on drive pulley 24. Again, when the tension is relieved, driven spools 5 will again engage the periphery of band 25 on drive pulley 24. It is believed that this engagement between driven disc 15 and drive pulley 24 and between driven spools 5 and drive pulley 24 in the normal operation during the feeding of film through the machine, will be of a bobbing nature. This will vibrate shaft 4 and film spools 5 carried thereby during the film feeding operation and agitate the feeding operation to secure

more efficient feeding of the film strip in each bank to effectively eliminate slack, as well as excessive tension. The operation is such that should slack develop on any of the idle spools, the tendency drive by positive rotation of shaft 4 in combination with the operation of driven spools 5 will automatically take up the slack in the spool bank and prevent excessive tension.

With the driven film spools 5 at the film leaving end of the spool bank, it will be understood that this positive film feeding operation in each bank will, in combination with the positive friction drive of shaft 4 normally tending to rotate idle film spools 5, produce a cooperation to control and eliminate slack and excessive tension on all film spools within the spool banks without in any manner interfering with the operation of adjacent spool banks and the control of slack and tension therein.

A modified form of drive is illustrated in Figs. 3 and 4. In this modified drive, the driven spool or spools 5 indicated by the numeral 26, is rigidly secured against rotation on shaft 4 by a pin 27 or other suitable means. In this form of the invention, drive pulley 22 and driven disc 15 are omitted so that all of the idle film spools 5 on shaft 4 will tend to rotate with positively driven shaft 4. Shaft 4 will be driven through driven spools 5 from drive pulley 24 at the same speed as driven spools 5, and the tendency to drive idle spools 5 will be at the same rate of speed as driven spools 5.

Whenever the film loops on idle spools 5 at the end of the spool bank opposite to driven spools 5 have the tension increased to an excessive amount, springs 10 may be compressed to compensate for the increased tension until it is transmitted throughout the length of shaft 4 to disengage driven spools 5 from drive pulley 24. Springs 10 at the end of shaft 4 remote from drive pulley 24 may be adjusted for the desired tension so that sufficient movement downwardly of the end of shaft 4 supported thereby will be provided to prevent excessive tension on the film loops until compensation is effected at the opposite end of shaft 4 with drive pulley 24 by moving driven spools 5 out of contact with the periphery of band 25. In this way, this modified form of film drive will control slack and excessive tension in each spool bank independently of adjacent spool banks, in the same manner as previously described, through the rotation of shaft 4 tending to drive idle spools 5 in combination with driven spools 5 by the operation of drive pulley 24 and the resilient mounting of shaft 4 by springs 10.

The invention claimed is:

1. In a drive for film processing machines, a support, an upper spool shaft, means at opposite ends of said shaft rotatably carrying said shaft and having a resilient mounting on said support for independent movement of each end of said shaft relative to said support, said upper spool shaft having a plurality of film spools rotatable thereon to form the upper series of spools in a spool bank, a drive shaft rotatably mounted on said support in spaced parallel relation above said upper shaft, a drive pulley on one end of said drive shaft having friction driving engagement and cooperation with a film spool at one end of the series on said upper shaft, and disengageable drive means between the opposite end of said drive shaft and said upper shaft for driving said upper shaft in the same direction as said driven film spool, said first-mentioned means normally moving said upper shaft toward said drive

shaft to retain said film spool in driving engagement with said drive pulley and said disengageable drive means in driving engagement, said upper shaft having opposite ends independently movable away from said drive shaft upon development of undesirable film tension for disengaging said film spool from said drive pulley and independently disengaging said drive means.

2. In a drive for film processing machines as claimed in claim 1, wherein said disengageable driving means on said drive and upper shafts is formed for cooperation to drive said upper shaft at a faster rate of speed in the same direction as said driven film spool for cooperation in eliminating the formation of slack and excessive tension in film loops carried on said film spools.

3. In a drive for film processing machines having a support, a spool bank having an upper shaft carrying a series of film spools rotatable thereon and resiliently suspended from said support, a drive shaft rotatable on said support in spaced parallel relation above said upper shaft, and a drive pulley on one end of said drive shaft having peripheral friction driving engagement with a film spool on the film leaving end of said upper shaft, the combination of means rotatably mounting said upper shaft relative to said support, a driven disc rigidly mounted on the opposite end of said upper shaft, and a drive pulley on the opposite end of said drive shaft having peripheral driving engagement with said disc for rotating said shaft in the same direction as said driven spools for cooperation in controlling slack and excessive film tension in film fed on said spools.

4. In a drive for processing machines, the combination of a support, a spool bank having an upper shaft carrying a series of film spools rotatable thereon, adjustable means resiliently and rotatably suspending said upper shaft from said support, a drive shaft rotatable on said support in spaced parallel relation above said upper shaft, a drive pulley on one end of said drive shaft having peripheral driving engagement with a film spool on one end of said upper shaft, and adjustable means normally retaining said film spool on one end in said peripheral driving engagement with said drive pulley, and disengageable means for positively rotating said upper shaft in the same direction as the film spool driven by said drive pulley through power transmission from said drive shaft, whereby excessive film tension on said film spool will move said upper shaft away from said drive shaft and disengage said film spool from said drive pulley and also disengage said disengageable means.

5. In a drive for processing machines as claimed in claim 4 wherein said means for positively rotating said upper shaft is formed for driving said upper shaft at a faster speed than said drive pulley to take up and eliminate slack and tension in a film strip being fed through a spool bank.
